UNITED STATES PATENT OFFICE.

EDGAR M. BOTTOOME, OF MOUNDSVILLE, WEST VIRGINIA, ASSIGNOR TO THE PALM BROTHERS COMPANY, OF NEW YORK, N. Y.

DESIGN FOR A PLATE OR SIMILAR ARTICLE.

60,768.

Specification for Design. Patented Apr. 11, 1922.

Application filed March 26, 1921. Serial No. 455,998. Term of patent 3½ years.

To all whom it may concern:

Be it known that I, EDGAR M. BOTTOOME, a citizen of the United States, residing at Moundsville, in the county of Marshall and State of West Virginia, have invented a new, original, and ornamental Design for a Plate or Similar Article, of which the following is a specification, reference being had to the accompanying drawing, forming part thereof.

The figure is a plan view of a plate showing my new design.

I claim:

The ornamental design for a plate or similar article, as shown.

EDGAR M. BOTTOOME.
